ABSTRACT OF THE DISCLOSURE

An ozonizer element of the type comprising a metal outer sleeve and a glass tube located within said sleeve and having an inner face which is at least partially metallized, said element comprising, in said glass tube, in roughly facing relation to the end of said metal sleeve, a metal deflecting ring having a roughly cylindrical portion in contact with said metallized layer and a curved remaining portion, the concavity of said curved portion facing the interior of said tube, whereby the distance between said ring and said wall of said tube increases progressively.

The present invention relates to apparatuses producing ozone, or ozonizers, of the type comprising a plurality of cylindrical silent discharge elements each of which consists of an outer metal sleeve and a glass tube disposed within said sleeve, the inner face of said tube being at least partially metallized.

The metallized layer and the metal sleeve are respectively connected to one of the ends of the high tension winding of a transformer and constitute the armatures of a capacitor between which is produced from a given voltage a silent discharge phenomenon which converts a part of the oxygen of the air flowing between these armatures into ozone. In apparatuses of this type, the yield of the ozone is of course a function of the maximum voltage it is possible to apply between the two armatures. However, it is not possible to increase this voltage as much as it would be desired, since parasitic effects, such as sparks, are produced in the regions of concentration of the lines of force which thus limit the operational characteristics of the apparatuses to values inferior to those which could theoretically be anticipated.

The object of the invention is to improve the apparatuses of the aforementioned type. The ozonizer element according to the invention comprises, in said glass tube, in roughly facing relation to the end of said metal sleeve, a metal deflecting ring having a roughly cylindrical portion in contact with said metallized layer and a curved remaining portion, the concavity of said curved portion facing the interior of said tube, whereby the distance between said ring and said wall of said tube increases progressively.

Preferably, the curved portion of the deflecting ring has a section of parabolic shape.

Owing to this deflector which extends the conductive layer, there is achieved a progressive and continuous separation of said conductive layer and the solid dielectric constituted by the glass tube. The electric field is thus better distributed and this eliminates the peak effects and allows the element to operate correctly under higher voltages.

Further features and advantages of the invention will be apparent from the ensuing description with reference to the accompanying drawing.

In the drawing:

FIG. 1 is a sectional view of an ozonizer element provided with a deflecting ring according to the invention, and

2

FIG. 2 is a perspective view of said ring removed from the silent discharge element shown in FIG. 1.

FIG. 1 shows a silent discharge element of a tube ozonizer of known type.

Such an element comprises mainly a cylindrical metal tube 1 in which is disposed a concentric electrode 2 which is also cylindrical and consists of a glass tube 2^a, the cylindrical portion of which is covered with a conductive layer 2^b.

10 The metal tube 1 is flared at 1^a and 1^b so as to constitute a field deflector and the glass tube 2^a extends beyond the two ends of the metal case. One end 3^a is closed and has a conical shape and the other end 3^b is open and corrugated.

15 In the tube 2 brushes 4 electrically connect the metal film 2^b to a conductor 5 which is connected to one of the terminals of the high tension winding of a transformer (not shown).

The tube 1 is connected to the other terminal of this high tension winding.

The end 3^b of the tube 2 is provided with a deflecting ring 6 which has a cylindrical portion 6^a and a curved portion 6^b whose concavity is directed inwardly of the tube 2.

25 The portion 6^a of the ring is in contact with the conductive film 2^b.

The curved portion of the ring has preferably a longitudinal section in the shape of arcs of a parabola. It is split at 7 (FIG. 2) throughout its length so as to enable it to be introduced in the tube 2 in such manner that, once it is mounted in the tube, it forms a minimum clearance which is almost nil between the two edges of the split 7.

35 This ring is preferably constructed from previously annealed polished steel so as to have good elasticity and has a thickness of about a few tens of a millimetre.

The advantage of the device according to the invention is important. The presence of the deflecting ring 6 at the end of the tube 2 precludes a peak effect at the end of the electrode constituted by the metal layer 2^b or, more precisely, increasing the voltage at which this peak effect is produced. This is due to the fact that the separation between the conductive material and the dielectric is achieved in a more progressive manner owing to the curved portion 6^b of the ring.

As the voltages created between the electrode 1 and the electrode 2^b are higher, the length of the corrugated insulating portion of the glass tube outside the tube 1 has to be increased relative to the length in conventional apparatuses.

Although a specific embodiment of the invention has been described, many modifications and changes may be made therein without departing from the scope of the invention as defined in the appended claims.

Having now described my invention what I claim as new and desire to secure by Letters Patent is:

1. In an ozonizer element comprising a metal outer sleeve and a glass tube located within said sleeve and having an inner face which is at least partially metallized; a metal deflecting ring in said glass tube in roughly facing relation to the end of said metal sleeve, said ring having a roughly cylindrical portion in contact with said metallized layer and a curved remaining portion, the concavity of said curved portion facing the interior of said tube, whereby the distance between said ring and said wall of said tube increases progressively.

2. The structure as claimed in claim 1, wherein the curved portion of said ring has a parabolic sectional shape.

3. The structure as claimed in claim 1, wherein said

ring comprises a longitudinal split extending throughout the length of said ring.

4. The structure as claimed in claim 1, wherein said ring is of annealed and polished steel.

5. An ozonizer element comprising in combination a metal outer sleeve, a glass tube located within said sleeve and having an inner face which is at least partially metallized and a metal deflecting ring in said glass tube in roughly facing relation to the end of said metal sleeve, said ring having a roughly cylindrical portion in contact with said metallized layer and a curved remaining portion, the concavity of said curved portion facing the interior

of said tube, whereby the distance between said ring and said wall of said tube increases progressively.
